CLAIM

The ornamental design for an athletic sock, as shown and described.

DESCRIPTION

FIG. 1 is a left side elevational view of an athletic sock, showing my new design, the right side being a mirror image thereof;

FIG. 2 is a top plan view thereof;

FIG. 3 is a front elevational view thereof;

FIG. 4 is a rear elevational view thereof; and

FIG. 5 is a left side elevational view of a second embodiment of that shown in FIG. 1, the right side being a mirror image thereof, and the top, front, and rear views being identical to FIGS. 2-4 respectively.

The bottom plan views of the two embodiments are flat and unornamented.

FIG. 1

FIG. 2

FIG. 3

FIG. 4

FIG. 5
